ABSTRACT

A drilling structure and method of constructing same which can be located in remote areas including a foundation composed of permanent foundation units, a substructure mounted on the foundation and a derrick mounted on the substructure for drilling for oil or the like in such remote areas. The permanent foundation units, the substructure and the derrick are all comprised of members that can be transported to the remote area by means of a helicopter or the like.

8 Claims, 11 Drawing Figures

METHOD OF CONSTRUCTING A REMOTELY LOCATED DRILLING STRUCTURE

BACKGROUND OF THE INVENTION

The field of this invention is oil well drilling or the like.

The vast amount of oil reserves located across the world that are relatively accessible are being quickly consumed. There are other oil reserves, many of which are untouched as of now, that are located throughout the world. However, many of these remaining oil reserves are located in areas which are inaccessible by means of conventional transportation. For the purposes of description herein, these inaccessible areas are defined as remote areas and may include oil-rich land that is surrounded by mountains, marshy or swampy land covered by relatively shallow water, or any other land located anywhere that is not easily reached by conventional ground transportation or conventional floating platforms.

SUMMARY OF THE INVENTION

It is an object of this invention to provide a new and improved drilling structure and method for constructing such a drilling structure which can be located at remote, areas throughout the world.

It is a further object of this invention to provide a drilling structure and method for producing same that is independent of a need for land vehicles during construction.

These and other objects of this invention are provided by a drilling structure which includes a foundation comprised of a plurality of foundation units, a substructure comprised of a plurality of interconnected frame members, and a derrick structure comprised of a plurality of derrick units which can be flown in to the remote area by helicopter or the like and are connected in a stacked arrangement by pin and sleeve connectors. The members or elements that comprise the permanent foundation units, the substructure and the derrick structure can all be flown into the remote area by means of a helicopter or the like.

The method of constructing such a derrick structure includes as a first step the construction of a temporary foundation for supporting a crane or other lifting apparatus. The temporary foundation is constructed by transporting by helicopter a plurality of temporary foundation units and positioning such units adjacently to support a crane thereon. The crane is then utilized to drive a series of pilings through jacket assemblies, which can be flown in by helicopter, in order to provide a solid, uniform permanent foundation for the derrick substructure and the derrick itself.

The derrick substructure is then assembled on the permanent foundation units by flying in substructure frame members and mounting same onto the permanent foundation units by lug and bolt connections.

A series of derrick modules or units are then flown in and stacked and interconnected by pin and sleeve connections in order to provide a derrick for drilling operations or the like. The derrick is an open type of derrick having a general U-shape. The interconnection of the stacked derrick units is provided by means of connector joints wherein each connector joint includes a pin inserted into a sleeve and locked in such connected position by a lock pin. Each of the connecting

sleeves further includes a frusto-conical guide sleeve for positioning the sleeves about the connector pins.

BRIEF DESCRIPTION OF THE DRAWINGS

FIG. 1 is an isometric view of the completed drill structure of the preferred embodiment of this invention which has been constructed according to the method set forth herein:

FIG. 2 is an isometric view of a partially completed temporary crane platform:

FIG. 3 is an isometric view of the temporary crane platform with a crane supporting base thereon:

FIG. 4 is an isometric view of the completed temporary crane platform and the crane utilized to construct 15 the permanent foundation units of this invention:

FIG. 5 is an isometric view of the construction of a first set of permanent foundation units:

FIG. 6 is a schematic view further illustrating the replacement of the temporary crane foundation with a 20 permanent foundation unit;

FIG. 7 is an isometric view of the completed foundation:

FIG. 8 is an isometric view of the derrick substructure:

FIG. 9 is a schematic view illustrating the lug and bolt connection used in the derrick substructure:

FIG. 10 is an isometric view of the completed, stacked derrick; and

FIG. 11 is a partially schematic and partially sectional view of the pin and sleeve joint connection utilized to secure the stacked derrick units.

DESCRIPTION OF THE PREFERRED EMBODIMENT

Referring to the drawings, the letter O generally designates the drilling platform of the preferred embodiment of this invention which is constructed in a remote area A according to the method of the preferred embodiment of this invention. By definition herein, the remote area A includes almost any area which is inaccessible by conventional land transportation or by conventional water vehicles, including floating drill platforms. That is, the remote area A includes regions which are mainly accessible by air transportation. In the embodiment of this invention illustrated in the drawings, the remote area A is a swampy region covered with shallow water W and having a bottom schematically designated B.

Basically, the drill structure O includes a foundation 50 F comprised of a plurality of foundation units 10. A derrick substructure S is mounted onto permanent foundation platform 11 and a derrick D is mounted onto the derrick substructures in order to provide a complete drill structure O for drilling for oil or the like in the remote area A. The oil well drill structure O of this invention is constructed entirely of members which have been flown into the remote area A by means of a helicopter H.

Referring in particular to FIGS. 2-4, the initial step 60 in the method of constructing the drilling platform O is to assemble a temporary crane platform or foundation generally designated as 12. The temporary crane platform 12 is assembled utilizing the helicopter H. The helicopter H is used to fly in four temporary foundations units or modules 14. Each of the modules 14 is identical in structure and thus like numbers and letters will be used to describe like parts.

Each of the units 14 include four jacket legs 14a, 14b, 14c and 14d. Each of the jacket legs 14a-14d are hollow, tubular members or pipes which are interconnected by bracing 14e. The bracing 14e includes horizontal brace members such as 14f and cross-brace members such as 14g. These brace members 14f and 14g are welded onto the legs such as 14a and 14b in order to properly support the legs 14a-14d in a square configuration or lattice. Jacket legs 14a-14d have mounted at the bottom thereof a support flange 14h. The support flange 14h is an annular flange welded or otherwise mounted onto the outside wall of the jacket legs 14a-14d in order to provide additional support for the temporary foundation unit 14 and the crane C to be mounted thereon.

The temporary crane platform 12 includes four of these temporary foundation units 14 which are flown in by the helicopter H and are positioned in a proximity to each other in order to provide an approximately square-shaped base to support the crane C. The annular flanges or pads 14h rest on the bottom B of the remote area H and thus serve to provide additional support and stability to the entire unit 12.

The temporary foundation units 14 are interconnected by two I-beams 15a and 15b which are mounted onto some of the top, horizontal bracing members 14f. Each of the I-beams 15a and 15b extend across two of the units 14 and are positioned parallel with respect to each other. The beams 15a and 15b support transverse I-beams 16a and 16b which extend between and are connected to the beams 15a and 15b. The beams 16a and 16b cooperate with shorter, support I-beams 17a and 17b, which are connected to the beam 16a and 16b, to support the crane center base member 18. A crane platform 19 of planks and the like are mounted onto the rectangular frame defined by beams 15a, 15b, and the side beams 15c and 15d.

The helicopter is then used to fly in the various components of the crane C, which may be a crane of any variety so long as the crane C is suitable for constructing the remainder of the oil well drilling platform O. The crane C includes a boom 20a mounted in a conventional manner and a pile driving apparatus 20b, also of conventional construction. The pile driving apparatus 20b operates in a well known manner and may be diesel-driven. The pile driving apparatus 20b includes a pile driving hammer 20c, the entire pile driving assembly being suspended from the boom 20a in order to drive piles such as the pile P illustrated in FIG. 4.

Using the helicopter H and the crane C operating from the temporary platform 12, the permanent foundation F is then constructed. The permanent foundation F includes the plurality of permanent foundation units 10. Each permanent foundation unit 10 includes a jacket module or unit 21 that is substantially identical in size and structure of the temporary foundation units 14. Thus, the jackets 21 include four hollow tubular jacket legs or pipes 21a-21d which are interconnected by bracing generally designated as 21e to form a square-shaped module. The jacket modules 21 are flown in by means of the helicopter H one-by-one and are positioned about the temporary crane platform 12.

Referring to FIG. 4, the first permanent foundation unit 10a is constructed by utilizing the helicopter H and the crane C to position the jacket module 21 substantially adjacent to the temporary crane platform 12. Then, the crane C and the pile driving apparatus 20b

is utilized to drive piling P through each of the tubular or pipe members 21a-21d into the bottom B. Thus, pilings P, which may be steel piles or of other suitable material, are driven into each of the jacket legs 21a-21d in order to provide one of the permanent foundation units 10. The hollow jacket legs 21a-21d serve as guides to the pilings as they are driven into the bottom B.

The first permanent foundation unit 10a is completed 10 by cutting off (or driving) the pilings P to a certain, design elevation. A rectangular frame 21g is then mounted onto the pilings P extending upwardly from the jacket legs 21a-21d. The frame 21g is a square-shaped frame which serves as a sub-platform to the permanent platform 11. The square-shaped frame 21g can be constructed elsewhere and flown as a unit or module by the helicopter H to the remote area A and mounted on the pilings P by welding or other suitable means. Of course, any suitable materials may be utilized to construct the square-shaped frame 21g.

Thus, each of the permanent foundation units 10 (including the first unit 10a) consist of a jacket assembly 21 having piling P driven through the legs 21a-21d thereof and a frame assembly 21g mounted on the top 25 thereof to form the subplatform for the platform 11. The crane C, operated from the temporary crane platform 12, is actually used to construct an entire ring or set R of permanent foundation units 10 (which includes the first permanent foundation unit 10a) about the 30 temporary crane platform 12. Then, a platform section 23 is mounted on top of the permanent foundation unit 10b, which is positioned across the first unit 10a. The crane C is then moved or skidded onto the platform 23 of the permanent foundation unit 10b. The crane, in its 35 new location on the permanent foundation unit 10b, is utilized to construct a second set, herein designated as R2, of permanent foundation units about second crane platform 23b. After the crane C from the permanent 40 foundation unit 10b has constructed all the permanent foundation units R2 that may be constructed from that point, the crane C is then moved to another location and another group or set of permanent foundation units are constructed. This process of moving the crane to new locations to give it a new range for cooperating 45 with the helicopter H to construct permanent foundation units 10 is continued until the complete foundation F is provided for as illustrated partly in FIG. 7.

Before the crane C is moved from the permanent foundation unit at 10b, the crane C is used to disassemble the temporary crane platform 12 and put in its place one permanent foundation unit 10c which is aligned with the other permanent foundation units in the peripheral ring of units R. Thus, the spacing of the permanent foundation units 10 is such that four jacket assemblies 14 can be mounted in proximity at the center for the temporary crane platform 12 and later removed and replaced with a single jacket assembly 21, pilings P and a rectangular frame 21g to form one permanent foundation unit 10c.

Referring to FIG. 7, upon completion, the permanent foundation units 10 are arranged in evenly spaced columns 10d for providing uniform support for a platform 11. A plurality of longitudinal frame members or beams 11a are mounted onto the unit frame tops 21g and extend throughout the foundation F along the columns 10d. The individual planks which form the platform 11 for the permanent foundation F are mounted onto

these beams 11a. In this manner, the permanent foundation units 10 are interconnected and the platform 11 is mounted on top of them such that the units cooperate to stabilize and support the substructure S and the derrick D and all the necessary drilling equipment. One further comment should be made with regard to control of elevation. Since the pilings P are cut off or simply driven to a certain design elevation, the rectangular frame members 21g mounted on each set of four piles of a permanent foundation unit 10 are also at a specific design elevation, which may be equal to or above the elevation of the individual pilings P. Thus, the permanent platform 11 mounted on the plurality of permanent foundation units 10 is also at a specific design elevation.

The derrick substructure S is then mounted onto the platform 11 of the permanent foundation F. The substructure S is a generally inverted U-shaped frame which is capable of supporting the derrick D. The substructure S consists of opposing, vertical composite side walls 25 having a horizontal platform section 26 extending therebetween. Each of the side walls 25 is composed of six frame units 25a which are stacked in two groups of three frame units each. The stack frame units 25a are interconnected by lug and pin connections 25b. The lugs of each connector 25b are mounted on one of the frame units 25a and extend to a point adjacent to another of the frame units 25a and a pin is mounted therethrough in order to secure the two frame units together. The helicopter H may be used to fly in each of the individual frame units 25a separately and the helicopter H and the frame C can cooperate to stack the frame units in the stacks of three.

Horizontal frame sections 26a are mounted onto and extend between the two side walls 25 in order to provide a generally inverted U-shaped structure. Connection between the horizontal frame units 26a and the side frame units 25a forming the side walls 25 is made by lug and bolt connections or joints designated as 27 (FIG. 9). Referring to FIG. 9, the portion of the horizontal frame section 26a illustrated has a male lug 26b extending therefrom into a recess formed by two lugs 27a and 27b mounted onto the side wall frame units 25a. A bolt 27c extends through aligned openings in the lugs in order to secure a firm connection therebetween. The lug and bolt connection 27 is utilized wherever necessary between the horizontal frame members 26a and the side frame members 25a to provide connection therebetween. A series of plates 28a-28g of steel or other material are mounted onto the tops of side frame members 25a and the horizontal frame sections 26a in order to provide a sturdy operating floor for the oil well derrick D. Such an operating floor would include the conventional features of such an operating platform including an opening 29a for the drill string and perhaps the rotary table, as well as platform sections such as 29b for stand pipe or the like. The various oil well drilling equipment such as mud tanks and the like can be positioned within or about the substructure S, itself.

A set 30 of four raised feet 30a are mounted onto the plate 28c; and, another set 31 of feet 31a are mounted onto the plate 28f. Each of the feet 30a and 31a include bolt holes adapted to receive matching feet on the derrick D.

The derrick D includes a base section 35, an intermediate section 36 and an upper or top derrick section 37. The general shape of the base, intermediate and top

sections of the derrick cooperate to provide an open ended derrick D, a configuration which is familiar to the art.

The derrick base 35 includes derrick base units 35a and 35b which are identical in structure. Each of the base units 35a and 35b includes legs 35c interconnected by horizontal and cross-bracing generally designated as 35d. Feet 35e are mounted onto each of the base units 35a and 35b. The feet 35e for the base units 35a and 35b are adapted for placement directly over the substructure feet 30a and 31b such that the base sections 35a and 35b can be mounted on the feet 30a and 31a by bolts or other suitable means. The top of each of the base sections 35a and 35b is formed by a triangular framework 35f which includes converging side members 35g which converge to an apex or top points generally designated as 35h. A male connector pin 38a is mounted onto each of the two top points 35h on each of the base sections 35a and 35b. The flow connector pin 38a (FIG. 11) extends vertically upwardly from the top or apex portions 35a and includes an opening 38b. An annular, horizontal shoulder 38c forms the base for the connector pin.

The intermediate derrick section 36 includes two derrick frame units 36a and 36b which are identical except, of course, for position. The derrick unit 36a is mounted onto the tops 35h of the base units 35a and 35b, and the derrick unit 36b is mounted or stacked onto the unit 36a. Each of the intermediate section derrick units 36a and 36b are U-shaped and include a rear portion 36c and side portions 36d and 36e. Four, vertical tubular legs 36g are interconnected by bracing members generally designated as 36h in order to form the side portions 36d and 36e and the rear portion 36c. The bracing generally designated as 36h may include horizontally positioned frame members and cross-braced members which interconnect the four legs 36g as illustrated.

Referring now in particular to the legs 36g which form the U-shaped frame units 36a and 36b, the bottom end of the legs include connector sleeve portions 38d. The connector sleeve portions 38d may actually be integrally formed with the legs themselves if the legs are in fact tubular members or pipes of sufficient inner diameter to fit over the connector pins 38a. In either event, the bottom of the legs 36g for each of the units 36a and 36b have hollow, circular recesses therein adapted to be mounted over connector pins 38a. Each of the connector sleeves 38d includes a guide means 38e mounted on the bottom thereof. The guide means 38e is a frustro-conically shaped sleeve section which converges to a top 38e' having a diameter substantially equal to the diameter of the connector sleeve portion 38d. The frustro-conically shaped sleeve section 38e is welded or otherwise attached to the bottom of the connector sleeve 38d. The frustro-conically shaped sleeve section 38e converges from the bottom or widest portion 38f to the top portion 38e' of minimum diameter in order to serve as a guide for centering the pin 38b.

Each of the guide sleeves 38d includes openings 38g in the wall thereof which are positioned to align with the opening 38b in the connector pin in order to receive a lock pin 50.

Thus, with respect to the intermediate section frame unit or module 36a, each of the legs 36g thereof have mounted on the bottom ends thereof connector sleeves 38d having guide sleeves 38e mounted thereon. In this

manner, the crane C (or the helicopter H) can easily lower the frame unit 36a onto the connector pins 38a mounted at the tops 35h of the base section 35a and 35b. Lock pins 50 then secure the pins 38a in the sleeves 38d in order to provide pin and sleeve connecting joints, which may be generally designated 38. Connector pins 38a are mounted on the top of each of the legs 36g for the intermediate section frame unit 36a.

Referring to the frame section 36b, connector sleeves 38d and guide sleeves 38e are mounted onto the bottoms of each of the vertical legs 36g and connector pins 38a are mounted on the tops of each of the legs. Thus, the crane C or helicopter can be utilized to lower the frame unit 36b onto the frame unit 36a, with the guide sleeves 38e functioning to center the connector pins 38a mounted on the top of the frame unit 36a into the sleeve portions 38d. Connector pins 38b are mounted onto the tops of the vertically positioned legs 36g for the frame unit 36b.

The top derrick section 37 includes four stacked top units 37a, 37b, 37c and 37d. The first top frame unit 37a includes a rear portion 40a and side portions 40b and 40c. The side portions 40b and 40c converge toward each other rather than being parallel. The derrick unit 37a is formed of tubular frame members 40d which are interconnected by any suitable bracing to form the rear section 40a and the side portions 40b and 40c. The tubular members or legs have connector sleeves 38d and guide sleeves 38e mounted at the bottom thereof and connector pins 38b mounted at the top thereof.

A second top frame unit 37b is mounted onto the first top frame unit 37a and includes similar side and rear portions 41a-41c. The side portions 41a and 41b are in alignment with the side portions 40b and 40c for the derrick frame unit 37a. The third and fourth top derrick frame units are basically identical in construction to the units 37a and 37b except that the side walls thereof converge such that the derrick D is provided with continuously converging side walls which converge to the top 44, wherein the crown block and other rigging may be mounted.

Thus, each of the sections of the derrick D including the base frame units 35a and 35b, the intermediate frame units 36a and 36b, and the top frame units 37a-37d may be flown in by helicopter H and stacked on top of each other and secured by the pin and sleeve connection means generally designated as 38 in FIG. 11, which is utilized to secure and assemble the entire network derrick D.

OPERATION AND USE

In operation and use of the method of assembling the oil well derrick platform O of the preferred embodiment of this invention, the helicopter H is first used to fly in the temporary platform units 14. The temporary platform units 14 are positioned in proximity to each other and rest on the bottom B. The annular flanges or pads 14a serve to stabilize and support the legs 14a-14d of each of the temporary platform units 14. The crane C is then mounted on the top thereof as previously described. The crane C is then used to assemble the first unit 10a of the permanent platform units 10. As previously mentioned, each of the permanent platform units 10 include piling P which is driven through the individual hollow tubular legs of the jackets 21. The pilings are cut off at design elevation and a square or

rectangular top frame 21g is mounted on the top of the piles.

The crane C is then used to construct the remainder of the permanent foundation units 21 in a ring R about the temporary crane platform 12. The permanent unit 10c is assembled after the temporary crane platform 12 is removed. Since the jackets 14 and 21 are identical, one of the temporary jackets 14 can be repositioned and used to form the permanent unit 10c. The crane is then moved to another location such as the permanent foundation unit designated by the number 10b. From the unit 10b, more units, such as a second set R2 of the permanent foundation units, are constructed. This procedure is continued until the entire plurality of permanent foundation units 10 are constructed and arranged in adjacent columns 10d illustrated in FIG. 7. The platform 11 is then mounted onto the frame members 21g thus completing the foundation F.

The substructure S is then positioned on top of the platform 11. Each of the side frame units 25a are flown in by helicopter and the crane C, operating on the platform 11, is utilized to assemble the frame units 25a into the inverted, U-shaped configuration illustrated in FIG. 8. As previously mentioned, the connections between the various frame units 25a and the horizontal frame units 26a is provided by lug and bolt connections 27.

The derrick D is then mounted on the top thereof. The derrick D is constructed by first flying in the two base units 35a and 35b and mounting them on the feet 30a and 31a on the platform plates 30 and 31, respectively. The first intermediate frame unit 36a is then mounted onto the pins 38a mounted at the tops 35h of the base units 35a and 35b. The guide sleeves 38e serve to center the sleeve portions 38d over the pins 38a as previously described. Lock pins 50 are then mounted into the aligned openings 38b and 38g in order to lock the pin connections and form joints generally designated as 38. The second intermediate frame unit 36b is then stacked onto the first intermediate frame unit 36a.

The top frame units 37a-37d are then stacked together to form the upper frame section 37, which has sides which converge to the top 44. The helicopter H is then used to fly in the standard oil well drilling equipment necessary to operate the oil well drilling platform O.

After the drilling operation is completed, the entire drilling platform O can be removed by helicopter H and reused at another location. That is, all the elements of the derrick D, the substructure S and the foundation F can be removed, including the jackets 21, and even the pilings P if desired.

Although certain configurations such as I-beams and tubular members have been described herein, it should be understood that any configuration for these elements may be utilized so long as they are of sufficient strength to support the weight of the entire platform.

The foregoing disclosure and description of the invention are illustrative and explanatory thereof, and various changes in the size, shape, and materials as well as in the details of the illustrated construction may be made without departing from the spirit of the invention.

I claim:

1. A method of constructing a drilling platform in remote areas, comprising the steps of:

assembling a temporary crane platform in the remote area said step of assembling said temporary crane platform including:
 transporting by air a plurality of temporary foundation units;
 setting said temporary foundation units in proximity to each other; and
 interconnecting said temporary foundation units with a temporary crane platform for supporting a crane only during an early phase of constructing said drilling platform;
 assembling a crane on said temporary crane platform;
 building a plurality of permanent foundation units, said step of building said plurality of permanent foundation units including:
 utilizing said crane to build a first set of permanent foundation units surrounding said temporary crane platform;
 moving said crane to one of said permanent foundation units in said first set;
 replacing said temporary crane platform with a permanent foundation unit; and
 utilizing said crane to build other of said permanent foundation units;
 utilizing said crane to assemble a derrick substructure on said permanent foundation units; and
 assembling a derrick substructure for drilling oil or the like in the remote area.

2. The method set forth in claim 1, wherein said derrick substructure is assembled by the steps of:
 transporting by air to said remote area substructure frame units; and
 connecting said substructure frame units together to

form a support base for said derrick.
 3. The method set forth in claim 1, wherein a permanent foundation unit is built by the following steps:
 transporting a foundation jacket to said remote area and locating said foundation jacket near said crane; and
 using said crane, with hollow portions of said jacket serving as guides, to drive piling into the bottom of said remote area.
 4. The method set forth in claim 3, including the step of:
 cutting off said piling to desired elevation.
 5. The method set forth in claim 1, wherein said permanent foundation unit is built by the steps of:
 using said crane to drive piling for said permanent foundation units.
 6. The method set forth in claim 5 including the steps of:
 driving said piling in a plurality of groups; and
 mounting a top frame assembly on each pile in each of said groups to form a plurality of permanent foundation units.
 7. The method set forth in claim 1, including the step of:
 arranging said plurality of permanent foundation units in substantially adjacent columns to provide uniform support for said derrick.
 8. The method set forth in claim 1, wherein said derrick is assembled by the step of:
 transferring derrick units to said remote area;
 stacking said derrick units; and
 securing said derrick units by connector pins.
